UNITED STATES PATENT OFFICE

JULIO C. MATALLANA, OF NEW YORK, N. Y.

COLLAPSIBLE SHOE RACK

Application filed May 14, 1929. Serial No. 363,025.

This invention relates to a rack especially designed for supporting shoes or the like, the primary object of the invention being to provide a rack of this character which 5 may be readily and easily folded into a small and compact article so that it may be readily transported or stored.

An important object of the invention is to provide a rack including a cloth cover so that 10 the articles supported therein will be enclosed and protected against dust or other foreign matter.

A still further object of the invention is the provision of a rack having pivoted leg 15 sections secured at the lower ends of the front legs of the rack so that the inclinations at which the shoes or articles positioned on the rack are held, may be changed to meet the requirements of the user.

20 With the foregoing and other objects in view which will appear as the description proceeds, the invention resides in the combination and arrangement of parts and in the details of construction hereinafter described and claimed, it being understood that changes 25 in the precise embodiment of the invention herein disclosed, may be made within the scope of what is claimed, without departing from the spirit of the invention.

30 Referring to the drawings:

Figure 1 is a perspective view of a shoe rack constructed in accordance with the invention.

Figure 2 is a sectional view through the 35 rack.

Figure 3 is an end elevational view of the rack showing the same in its folded position.

Figure 4 is a fragmental elevational view 40 showing the rack equipped with means whereby it may be hung on a wall.

Figure 5 is a fragmental plan view of the curtain supporting frame.

Figure 6 is a sectional view taken on line 45 6-6 of Figure 2.

Figure 7 is a sectional view taken on line 7-7 of Figure 2.

Referring to the drawings in detail, the 50 reference character 5 designates one of the end sections of the frame of which the rack

is constructed, and the reference character 6 designates the opposite end section of the rack or frame, the end sections being identical in construction.

Each of the end sections includes a rear 55 bar 7 and a front bar 8, the bars 7 and 8 being connected by the horizontal bars 9 that have their ends connected to the bars 7 and 8 by means of the bolts 10 that extend through aligning openings in the bars providing pivotal connections so that the bars 7 and 9 may be folded into close engagement with each other when it is desired to fold the rack for storing or transportation.

Extending from each bar 7 is a pin 11, the 65 pins of the bars 7 being spaced from the upper ends of the bars 7, where they receive the hook ends 12 of the arms 13, which are pivotally connected to the forward bars 8 of the end sections. These arms 13 act to hold 70 the bars 7 and 8 of the end sections in proper spaced relation with each other, when the rack is in its extended position.

The bar 14 connects the rear bars 7, at their 75 upper ends, so that the bars 7 of the rear sections will be held in proper spaced relation with each other at all times. Pairs of bars 15 connect the bars 9 of the end sections, the bars 15 being spaced apart so that a shoe may rest thereon, in a manner as shown by Figure 80 2 of the drawings.

Hingedly connected to the lower ends of the front bars 8 of the end sections, are pivoted leg members 16 which may be folded inwardly in a manner as shown by Figure 1, 85 whereupon the supporting bars 15 are disposed in horizontal spaced relation with each other, but should it be desired to elevate the front portion of the rack, the pivoted leg members 16 may be moved to their extended 90 positions as shown by Figure 2, causing the bars 9 to take inclined positions.

Screw eyes 17 extend laterally from the rear bars 7 and provide supports for the end sections 18 of the curtain support 19 to which 95 the curtain 20 is secured, as by means of the curtain rings 21. Supported by the bar 14 is a box-like container 22 which is provided with a hinged cover 23 in which may be positioned articles of apparel. A hasp 24 is 100

provided on the cover so that the cover may be locked.

Screw eyes 25 extend upwardly from the upper ends of the bars 7, and provide a support for the rack, should it be desired to hang the rack on a supporting surface.

From the foregoing it will be seen that due to the construction shown and described the rack may be readily and easily folded into a small and compact article and may be readily moved to its extended position when it is desired to use the rack for supporting articles thereon.

I claim:

15 A rack comprising a frame embodying end sections, each end section comprising short front bars and substantially long rear bars, pivoted horizontal bars connecting the front and rear bars of each end section, supporting bars connected with the horizontal bars and arranged in parallel spaced relation with each other, extension leg members pivotally connected to the lower ends of the front bars to lengthen or shorten the front bars of the end sections to hold the bars connecting the front and rear bars of the sections, in inclined positions or horizontal positions.

20 In testimony that I claim the foregoing as my own, I have hereto affixed my signature.

JULIO C. MATALLANA.
